C. A. SPEARS

DEPTH REGULATOR FOR EXCAVATORS

Filed June 1, 1925

FIG. 4

FIG. 1

FIG. 2

INVENTOR.
CHARLES A. SPEARS

BY Harry S. Schwedler
ATTORNEYS.

UNITED STATES PATENT OFFICE.

CHARLES A. SPEARS, OF OAKLAND, CALIFORNIA.

DEPTH REGULATOR FOR EXCAVATORS.

Application filed June 1, 1925. Serial No. 33,984.

My invention is a depth regulator for excavators and is particularly adapted for use with or attachment to excavators of the endless bucket type in which the bucket carrying frame is pivotally mounted on a supporting carriage or the like.

My invention is applied to a bucket excavator and comprises a shoe pivotally connected to the lower end of the bucket elevator frame and having a crank arm and a link connecting the rear part of the shoe to the supporting carriage. When the crank is turned in one direction, it elevates the rear end of the shoe, thereby tipping the nose downwardly and allowing the bucket conveyor to dig deeper into the material being excavated. In this operation the bucket conveyor frame pivots backwardly on the supporting carriage.

When the crank is operated to be swung forwardly the shoe and its connecting bar forces the elevator frame outwardly and up, thereby elevating the bucket conveyors above the ground permitting the carriage to move the whole device forwardly. In this operation the bucket frame pivots upwardly on the supporting carriage.

The machine disclosed herein is an improvement on my application, Serial No. 748,608 filed November 8, 1924, for a depth regulator for surfacing and scraping machines.

My invention will be more readily understood from the following description and drawings, in which—

Figure 1 is a side elevation of an excavator of the endless bucket type with my depth regulator shoe and its operative mechanism connected thereto.

Figure 2 is a side elevation of the lower part of Figure 1 showing the shoe drawn rearwardly and tilted thereby allowing the excavator buckets to dig deeper.

Figure 3 is a view similar to Figure 2 with the shoe forced forwardly, thereby shoving the bucket excavator frame up and the buckets out of contact with the ground to facilitate transportation, etc.

Figure 4 is a detail showing the action of the crank arm and the crank pin bar in the various positions of the excavator.

Referring particularly to Figure 1 the excavator carriage is designated generally by the numeral 1 having a rigid frame 2 and caterpillar tracks 3 to move the carriage. The power mechanism for operating

the carriage and the excavator buckets will also be mounted on the carriage. The excavator frame 4 is pivotally connected to the carriage 2 by the pintle 5. This frame preferably has a pair of side rails 6 carrying the axles 7 for the lower and upper drums 8 over which the belt 9 passes, carrying the usual buckets 10.

The depth regulator shoe 11 has a substantial bar 12 rigidly connected thereto, preferably by having the rear part of the bar bent as indicated at 13 and riveted as at 14 to the middle of the shoe. The front end of the shoe is attached to the bar 12, by a brace 15 riveted at 16 to the nose of the shoe at 17, and secured by rivets 18 to the bar. The front end of the bar is swiveled on a pintle 19 which is fastened to one of the side rails 6. The rear end of the shoe is pivotally connected to a link 21 by the pins 22. The upper end of the link is pivoted to a crank 23 by a crank pin 24. The link is adjustable in the manner of a turn-buckle by having opposite threads 25 threaded into sockets 26 in a lower yoke 27 and an upper yoke 28. The central portion of the link is squared to form a wrench grip 29. By means of this link the distance between the pin 22 and the crank pin 24 may be adjusted.

A shaft 30 extends across the lower bars 31 of the carriage frame and has a substantial worm gear 32 keyed thereon. The cranks 23, of which there would be one on each side of the frame, are also keyed on the shaft 30, or otherwise secured in a rigid manner thereto. A worm 33 forming part of the worm shaft 34 is mounted in a lower bearing 35 and an upper bearing 36 attached by a brace 37 to the carriage frame 2. A wheel 38 is used to operate the worm shaft and the worm.

A substantial brace 39 is bolted to the lower corner 40 of the lower member 41 of the excavator frame 4 and continues substantially parallel thereto and then upwardly, having a central portion 42 parallel to the inclined back frame member 43 of the bucket frame, being bolted thereto as indicated at 44. It is preferable to have the crank pin 24 extend completely across the machine and connect at its ends to opposite links 21. The depth regulating mechanism just described is duplicated on the opposite side of the machine in a manner readily understood. Thus, there is another bar 12

pivoted to the other rail 6, to carry the opposite side of shoe 11, which is actuated by another link 21 and by crank 23, carried by shaft 30. There is, of course, only one shaft 34 with its attendant elements, and only one shoe.

The operation of my depth regulator shoe and the mechanism connected therewith is substantially as follows:

- 10 For normal digging or excavating in a forward direction the shoe 11 would rest on the ground as shown in Figure 1, in which case the carriage would be moved forward to cause the buckets to dig into new material.
- 15 When it is desired to dig deeper, hand wheel 38 is operated, turning the worm 33 to draw the cranks 23 rearwardly as shown in Figure 2. This elevates the rear portion of the shoe and tilts it forwardly, thus allowing the excavator buckets to dig deeper, as the shovel plate 45, which is attached by braces 46 and 47 to the bucket frame 4, is tilted into the soil.

If the excavator is operating in soft material a slight tilting of the shoe, throwing the weight on the nose portion 17 will allow the buckets to work their way down in the material being excavated. When the required depth is reached the hand wheel 38 will be reversed bringing the crank 23 and link 21 into the position shown in Figure 1 with the shoe 11 horizontal.

When it is desired to swing the bucket frame 4 upwardly on its pintle 5 the hand wheel 38 is operated to swing the crank 23 forward, as shown in Figure 3. This will force the shoe 11 forward and through the bar 12 shove the lower end of the bucket excavator frame upwardly and outwardly thereby raising the buckets and the shovel plate 45 above the ground. The whole machine is therefore in a position for being transported on the caterpillar tracks 3 from place to place.

45 The brace 39 and the rearward surface of the inclined back frame member 43 form a slot in which the crank pin bar 24 operates. Thus, in the movement of the crank forwardly or backwardly the crank pin bar presses either against the brace 39 or the back of the frame member 43, thereby functioning in part to position the forward end

of the excavator. The different positions of the crank pin bar 24 are shown in Figure 4 in which the solid line position is that 5: represented by the working position of Figure 1 and the upper dotted position would be that with the shoe raised and drawn backwardly to a greater extent than in Figure 2. The lower dotted circle indicates the position of the crank pin bar when the excavator is in the lifted position of Figure 3. It will, of course, be recognized that the frame member 43 shifts in position relative to the pintle 5 in these various shifting 6: movements.

My invention may be considerably modified in general structure and in details to suit special requirements, sizes of machinery and other circumstances without departing 7 from the spirit thereof.

Having described my invention, what I claim is:

1. The combination with an excavator having a carriage frame, a shovel plate and a bucket conveyor associated therewith, of an excavator frame for supporting said plate and conveyor, said excavator frame being pivoted to the carriage frame, a bar pivoted to the excavator frame, a shoe carried by said bar and adapted to slide over the ground, and means connecting said shoe with the carriage frame, whereby the excavator frame may be tilted relative to the carriage frame.

2. The combination with an excavator having a carriage frame, of an excavator frame pivoted thereto, a shoe associated with said excavator frame, and means connecting said shoe with the carriage frame, whereby the excavator frame may be tilted relative to the carriage frame.

3. The combination with an excavator having a carriage frame, of an excavator frame pivoted thereto, a shoe associated with said excavator frame, and means connecting said shoe with the carriage frame, whereby the shoe may be raised out of engagement with the ground, and the excavator frame tilted relative to the carriage frame.

In testimony whereof I affix my signature.

CHARLES A. SPEARS.
